TIMER MECHANISM

George C. Fields, Euclid, Ohio, assignor to The
Apex Electrical Manufacturing Company,
Cleveland, Ohio, a corporation of Ohio

Application May 9, 1941, Serial No. 392,722

10 Claims. (Cl. 192—139)

This invention relates to a timer mechanism and more particularly to a mechanically driven timer mechanism suited for use on a domestic washing machine.

It is among the objects of my invention to provide an improved timer mechanism to control the operating period of a washing machine agitator shaft and the present invention relates to an improvement in the type of timer mechanism such as is disclosed and claimed in the patent to Martin E. Rhode, No. 2,244,803.

It is an object of my invention to provide a timer mechanism which is adapted to be driven by an eccentric on an oscillating agitator shaft and wherein a pair of co-axially arranged fast and slow ratchets are progressively advanced during the period of agitator oscillation so as to operate a clutch associated with the agitator drive mechanism.

It is a further object of my invention to provide a timer mechanism made according to the preceding objects in which the ratchets and a cam moved thereby are mounted on a single shaft so that the timer may be reset and advanced through its cycle of operation by manually advancing said shaft.

Further objects and advantages relating to dependability in operation, simplicity in construction and low cost of manufacture will appear from the following description and the appended drawings, wherein

Figure 1 is a perspective view of a timer made according to my invention, assembled with a washing machine drive mechanism;

Figure 2 is a plan view of the timer and associated agitator drive parts;

Figure 3 is an elevation with parts in section taken as indicated in lines 3—3 of Figure 2;

Figure 4 is an elevation of the timer taken as indicated in lines 4—4 of Figure 2;

Figure 5 is a sectional view taken on the plane indicated at 5—5 of Figure 3;

Figure 6 is a sectional view taken on the plane indicated at 6—6 of Figure 3; and

Figure 7 is a sectional view taken on the plane 1—7 of Figure 3.

I have shown my invention as used in conjunction with a washing machine mechanism of the type wherein the drive to the oscillating agitator may be interrupted without interrupting the drive to the wringer, such as for instance, the mechanism disclosed in the patent to Wied 50, 2,237,919.

It will be appreciated, however, as the description proceeds that my timer mechanism may be employed in other types of washing machine drive mechanisms and in other types of machinery.

Referring to the drawings, the driving mechanism for the washing machine is indicated in 55 its entirety as at 6, the gear case thereof sup-

porting and housing the gears and linkage for transmitting movement from the driving shaft 8 to the oscillating agitator shaft 9 and to the continuously rotating wringer shaft 10.

5 The shaft 8 may be continuously rotated by an electric motor, gasoline engine or other power unit. Rotating motion of the shaft 8 is transmitted to a main driving gear 11 which is a composite gear and transmits its movement to idler gear 12 and gear 13 fixed to the wringer drive shaft 10. An eccentric member 14 may be clutched to the gear 11 so as to rotate therewith and oscillate the agitator shaft 9 as shown and described in said Wied patent. The engagement and disengagement between the eccentric 14 and the gear 11 is effected by moving the clutch plunger 16 to and from a recess in the gear 11 by means of a clutch operating shaft 17 and its associated operating arm 18. The clutch shaft 17 is urged to turn the clutch parts in the direction of the arrow 19 by means of the tension spring 20 which is secured at one end to the plate 18 and at the other end to the gear case so as to tend to turn the clutch operating link 20 extending to the timer in the direction of the arrow 21.

30 The timer mechanism in its entirety is indicated as at 22 and comprises a pair of ratchets adapted to be advanced by means of a pawl carriage oscillated by the arm 23. An arm 23 is pivotally supported as at 24 on the gear case and one end thereof as at 25 bears against an eccentric 26 secured to the agitator shaft 9. The other end of the oscillating arm 23 is provided with a link 27 operatively connected to the driving pawl for the timer. The main shaft 30 of the timer is provided with a universal joint 31 connecting the shaft 30 to an operating shaft 32. The arrangement last described is such 35 that the shaft 32 may project beyond the outline of the washing machine where it may be manually turned so as to advance the timer shaft 30 through its cycle of operation and thus 40 the clutch shaft 17 may be manually operated through the timer mechanism by the shaft 32.

45 Preferably the timer is mounted on the exterior of the gear case 7 by means of bolts such as 35 extending downwardly through the main supporting plate 36 of the timer. The main supporting plate 36 carries a sub-frame 37 which is secured to the plate 36 by a bolt 38 and a bolt 39, the bolt 39 being arranged to project downwardly through a slot 40 in the supporting plate 36 so that the entire timer unit may be adjusted on the supporting plate by loosening the bolt 39 and swinging the timer as a unit about the bolt 38, as 50 permitted by the slot 40. This adjustment provides for variations in manufacture and facilitates the correct alignment and arrangement of the operating parts.

55 The sub-frame 37 includes an upturned ear 41

which serves as a bearing support for one end of the timer shaft 30. A similarly upturned portion 42 serves to support one end of a second bearing plate 43. A downwardly turned ear 44 serves to support the bearing plate 43 beneath the main timer shaft 30. A third bearing plate 45 is secured by means of a rivet or the like 46 to the plates 42 and 43. A part of the bearing plate 45 extends forwardly of the ratchet disc assembly and is secured to a similar extension on the member 43 by means of a bolt and nut fastener 47.

A depending ear 48 of the plate 45 is arranged in alignment with the depending ear 44 of the sub-frame and in alignment with a depending ear 49 of the plate 43 and said ears are secured in such aligned positions by means of the bolt and nut fastening 50. Said last-named fastener and the aligned ears of the bearing plate also serve to support a keeper pawl assembly on the lower part of the timer mechanism.

A driving pawl assembly or carriage is pivotally mounted on the main shaft 30 and said assembly comprises a pair of spaced links 52 and 53 which are freely mounted for rocking movement on the main shaft 30 and are secured to each other at their upper ends by means of the bolt and nut fastener 54. A sleeve 55 is mounted on the fastener 54 and serves as a bearing support for a pair of driving pawls 57 and 58, which pawls are adapted to engage a slow-moving ratchet 59 and a fast-moving ratchet 60.

The pawls are normally urged about their pivotal mounting on sleeve 55 in the direction of the ratchets by springs 61 and 62 and upon each reciprocation of the driving pawl assembly, the pawl 58 engages a tooth in the fast moving ratchet 60 so as to advance said ratchet one tooth. A hold-out cam 64 is arranged alongside of the ratchet disc 60 and is operatively connected thereto by pin 65 so as to rotate therewith. The width of the pawl 57 is such that it overlaps a portion of the hold-out cam as well as a portion of the slow-moving ratchet disc 59, and thus the hold-out cam prevents the pawl 57 from advancing the slow-moving ratchet disc 59 upon each reciprocation of the driving pawl assembly. When, however, notch 64a of the holdout cam 64 is brought into position, beneath the pawl 57, said pawl will be lowered so as to engage a tooth of the slow-moving ratchet disc. Thus the slow-moving ratchet disc 59 will be advanced one tooth in response to a complete revolution of the fast-moving ratchet disc and its associated hold-out cam 64.

In the embodiment illustrated, there are 40 teeth on each of the ratchets and thus the slow-moving ratchet advances one tooth each time the fast-moving ratchet advances 40 teeth. Ordinarily it is desired to oscillate the agitator shaft about 60 times per minute for efficient washing of the clothes and thus the 40 to 1 ratio between shaft 9 and slow moving ratchet provides a convenient angular movement in the operating and resetting parts of the timer.

It will be appreciated by those skilled in the art that the number of teeth on the ratchet discs and the ratio between the ratchet discs may be varied within relatively wide limits.

As shown in Figures 4 to 7, the main shaft 30 of the timer is flattened for a portion of its length and the slow-moving ratchet disc 59 is provided with a central aperture fitting the flattened portion of the shaft 30 so that the advancing movement of the slow-moving disc will advance the shaft 30 therewith.

The advancing movement of the shaft 30 in response to movement of the slow-moving ratchet disc is transmitted through a cam and latch arrangement so as to effect a movement of the clutch shaft 30. An operating link 70 is secured to the plate 18 which is fastened to the clutch shaft 17 and said link 70 is normally urged in the direction of arrow 21. The tendency of the member 70 to move in said direction is in turn transmitted to a lever 71 which is fulcrumed on the shoulder 72 of the bolt 50.

The lever 71 is shaped as best illustrated in Fig. 4 and is slotted as at 71a so that it may be rocked about its pivotal mounting on bolt 50. An integrally formed ear 73 on the lever 71 projects laterally from the lever so as to overhang both the operating cam 74 and the spring-pressed latch 75, which latch is urged in a clockwise direction by the coil spring 46a which surrounds the rivet 46. The arrangement just described being such that when the cam 74 is turned in a clockwise direction (Fig. 4) the ear 73 and the lever 71 are carried to the position shown in Fig. 4, wherein the ear is latched in the position shown. This may be referred to as the "on" position of the main clutch in the agitator drive mechanism, inasmuch as the clutch member 16 is then positioned in the notch on gear 11 so as to oscillate the agitator shaft 9.

The cam 74 is provided on its periphery with three operating portions, namely an "on" portion extending from 74a to 74b, a reset portion extending from 74b to 74c and a release portion extending from 74c to 74a. The cam is shown in Fig. 4 as being in the "on" position and is advancing clockwise without effecting any change in the latched position of the lever 71. When, however, the cam has advanced approximately 90° from the position shown in Fig. 4, a lug 76 on the cam will be brought to bear against the portion 77 of the latch 75. Further advance of the cam and its lug 76 will rock the latch 75 downwardly so that the lever 71 may swing in a counter-clockwise direction about its pivot 50 in response to the spring tension imposed on the lever 71 through the medium of the link 70. The ear 73 is thus free to move into the "off" portion of the cam 74; that is, into the open space of the cam between point 74a and 74c. The last described movement of the lever 71 and the link 70 rocks the clutch shaft 17 into "off" position so as to interrupt the drive to the agitator shaft.

When it is desired to start the agitator through a new cycle of washing operation, the shaft 30 is manually advanced so as to bring the reset portion of the cam 74c-74b around to bear against the ear 73. The reset portion of the cam is the high point of the cam surface and rocks the lever 71 to an "on" position as shown in Fig. 4. The lug 76 on the cam plate is moved free of the latch portion 77 as the reset portion of the cam rocks the lever 71 clockwise and the latch 75 moves upwardly so as to catch and hold the ear 73 in its "on" position.

It will be understood that the shaft 32 which is coupled to the shaft 30 of the timer projects beyond the washing machine supporting structure and that said shaft and the tub supporting structure may carry appropriate indicia showing the "on," "off" and "reset" position of the cam 74.

In the timer mechanism illustrated and applied to a washing machine drive as shown, I have found that the "on" portion of the cam;

that is, the portion from 74a to 74b may maintain the clutch in an "on" position for about fifteen minutes and thus the indicia on the exterior of the washing machine would be marked to show that the full operating cycle would occupy fifteen minutes of agitator operation. To operate the agitator for a lesser period of time, the shaft 32 is manually advanced through a portion of the operating cycle. Thus the timer may be set to operate for a period of fifteen minutes or any period less than fifteen minutes, as may be desired by the operator of the machine.

Each of the ratchet discs 59—60 is provided with a spring-pressed holding pawl to prevent a counter-clockwise movement of the ratchet discs, as the driving pawl assembly swings through the counter-clockwise phase of its operating stroke. The holding pawl 80 being arranged as shown in Fig. 5, to prevent counter-clockwise movement of the ratchet disc 60, and the holding pawl 81 being arranged as shown in Fig. 7 to restrain counter-clockwise movement of the ratchet disc 60, the two holding pawls are pivotally mounted on the sleeve surrounding the bolt 50 and the pawl 81 is proportioned to overlap both the ratchet disc 50 and a hold-out cam 82 which is apertured so as to be fixed to turn with the shaft 30.

The hold-out cam 82 is shaped as shown best in Fig. 7 and is fixed to the shaft 30 so that the high portion of the hold-out cam rocks the holding pawl 81 out of engagement with the ratchet 50 when the reset portion of the cam 74 is in engagement with the ear 73 on the lever 71. Thus the hold-out cam frees the shaft 30 and the entire assemblage of parts fixed thereto so that the shaft 30 may turn in a counter-clockwise direction in the event that the lever 71 is not moved to its fully latched position as shown in Fig. 4. The hold-out cam in the above described manner guards against the operator inadvertently turning the lever 71 to a partly clutched position; that is, where the clutch shaft 17 effects only a partial engagement of the main clutch for the agitator drive. As soon as the hold-out cam 82 frees the ratchet assembly for counter-clockwise movement, the tension spring 20 is effective through the lever 71 to rotate the cam 74 counter-clockwise and position the parts in a fully "off" position.

A spacer plate 84 is arranged between the disc 64 and the ratchet disc 59. A depending portion of the disc 84 is provided with a slot to embrace the fastener 50 so as to maintain the member 84 non-rotatable. The provision of the member 84 prevents the movement of the fast-moving ratchet 60 and its associated member 64 from being transmitted by friction to the slow-moving ratchet 59. A similarly shaped disc 85 is arranged between the hold-out cam 82 and the arm 52 of the oscillating driving pawl assembly so that the oscillating movement of the driving pawl assembly will not be transmitted by friction to the hold-out cam 82 which is fixed to the shaft 30.

Referring generally to the timer and its associated washing machine drive mechanism, it will be assumed that the clutch shaft 17 is in an off position and the agitator shaft 9 is not turning. The cam 74 will then be advanced substantially 90° from the position shown in Fig. 4 and the lever 71 will be moved counter-clockwise so that the ear 73 is disposed at the "off" portion of the cam 74. When it is desired to start the agitator through its washing cycle, the shaft 32 is manually turned so as to move shaft 30 in a

clockwise direction so as to advance the cam 74 against the ear 73 through the reset portion of the cam 74b—74c. The movement of lever 71 imparted thereto by cam 74 throws the clutch shaft 17 to its "on" position. The latch 75 thereupon engages the ear 73 so as to maintain the lever 71 and the shaft 17 in its "on" position. The shaft 30 may be further manually advanced to a position such as shown in Fig. 4 where about seven and one-half minutes of movement remains on the portion of the cam 74 between 74a and 74b. The oscillation of the agitator shaft 9 is effective to rock the lever 23 and its related link 21 so as to oscillate the driving pawl assembly. The driving pawl 58 advances the fast-moving ratchet disc 60 one tooth upon each oscillation of the driving pawl assembly. Upon each complete revolution of the fast-moving ratchet disc 60, the ratchet disc 50 is advanced one tooth. The ratchet disc 59 being fixed to the shaft 30 advances the cam 74 a like amount. After about seven and one-half minutes operation of the agitator, the cam 74 has advanced to the position shown in Fig. 1, wherein the lug 76 is about to move the latch 75 away from the ear 73. As soon as the ear 73 is free of the latch 75, the lever 71 will swing about its pivot 50 as permitted by the slot 73 and thus move the clutch shaft 17 to an "off" position and terminate the operating cycle.

Although I have illustrated and described one form of my invention in considerable detail, it will be appreciated by those skilled in the art that numerous variations may be made therein such as for instance variations in the contour of the operating cam, in the arrangement of the pawls, ratchets and operating linkages connected therewith, without departing from the scope of the invention as defined in the following claims.

I claim:

1. A timer of the type controlling the period of operation of a driven shaft comprising a gear case for supporting said shaft, a clutch control adapted to be moved so as to interrupt the drive to said driven shaft, an eccentric turned by said driven shaft, a timer shaft, a plurality of ratchet discs mounted on said timer shaft, at least one of said discs fixed to said timer shaft, an oscillating pawl assembly having pawls adapted to engage said ratchet discs, means operatively connecting said eccentric and said pawls to oscillate said pawls and progressively advance said ratchet discs and means operatively connecting said timer shaft and said clutch control so as to move said clutch control after a predetermined number of oscillations of said pawls.

2. A timer for controlling the period of operation of a driven shaft comprising mechanism for driving said shaft, a clutch control operatively connected to said mechanism adapted to be moved so as to interrupt the drive to said driven shaft, an eccentric on said driven shaft, a timer shaft, a plurality of ratchet discs mounted on said timer shaft, at least one of said discs fixed to said timer shaft, an oscillating pawl assembly having pawls adapted to engage said ratchet discs, means connecting said shaft eccentric and said pawl assembly to intermittently advance said one ratchet disc and means operatively connecting said timer shaft and said clutch control so as to move said clutch control and interrupt the drive to the driven shaft after a predetermined number of oscillations of said pawls.

3. A timer of the type effecting movement of a control in response to a predetermined number

of oscillations of an oscillating driving member comprising a timer shaft supported for rotating movement, a slow-moving and fast-moving ratchet disc mounted on said shaft, an oscillating pawl carriage having pawls adapted to engage said ratchet discs, said slow-moving ratchet disc being fixed to said timer shaft and said fast-moving ratchet disc being free of said timer shaft, means to connect said oscillating driving member to said pawl carriage and progressively advance said ratchet discs, a cam fixed to said timer shaft and an operative connection between said cam and said control.

4. A timer for effecting movement of a control in response to a predetermined number of oscillations of an oscillating driving member comprising a timer shaft supported for rotating movement, a slow-moving and fast-moving ratchet disc coaxially mounted on said shaft, an oscillating pawl carriage having pawls adapted to engage said ratchet discs, means to connect said oscillating driving member to said pawl carriage, means to advance said fast-moving ratchet disc upon each oscillation of the pawl carriage and said slow-moving disc in response to a number of oscillations of the pawl carriage, a cam fixed to said timer shaft and an operative connection between said cam and said control to move said control in response to a predetermined number of advancing movements of the slow-moving ratchet disc.

5. A timer comprising a supporting plate, spaced bearing ears carried by said plate, a timer shaft mounted for rotation in said ears, a slow-moving ratchet and a fast-moving ratchet mounted on said timer shaft, a cam disc arranged between said ratchet discs, the major portion of the periphery of said cam disc exceeding the maximum diameter of the slow-moving ratchet, said cam disc connected to said fast-moving ratchet so as to rotate therewith, oscillating driving pawls mounted on a pawl carriage, one of said pawls adapted to engage said fast-moving ratchet and advance the same upon each oscillation of the carriage, another of said pawls arranged to engage the periphery of said cam disc and said slow-moving ratchet, whereby said last-named pawl is held in an inoperative position with respect to the slow-moving ratchet during the major portion of the movement of the cam disc.

6. A timer comprising a supporting plate, spaced bearing ears carried by said plate, a timer shaft mounted for rotation in said ears, a slow-moving ratchet and a fast-moving ratchet mounted on said timer shaft, a cam disc having a notch in its periphery arranged between said ratchet discs, the periphery of said cam disc on each side of said notch exceeding the maximum diameter of the slow-moving ratchet, said cam disc connected to said fast-moving ratchet so as to be moved thereby, driving pawls mounted on an oscillating pawl carriage, one of said pawls adapted to engage said fast-moving ratchet and advance the same one tooth upon each oscillation of the carriage, another of said pawls arranged to engage the periphery of said cam disc and said slow-moving ratchet, whereby said last-named pawl is held out of engagement with the slow-moving ratchet until the notch of the cam disc is carried beneath said pawl.

7. A timer comprising a shaft, a ratchet fixed to said shaft, a second ratchet freely rotatable

on said shaft, a reciprocating pawl carriage, a pawl on said carriage engaging said second ratchet, a cam disc rotated by said second ratchet, a second pawl on said carriage riding on said cam disc, a notch in said disc adapted to receive said second pawl, said second pawl engaging said first ratchet when in said notch, whereby said first ratchet and shaft are advanced in response to a predetermined number of pawl reciprocations and a control operatively connected to said shaft and moved thereby.

8. A washing machine clutch timer comprising a shaft, a ratchet fixed to said shaft, a second ratchet freely rotatable on said shaft, a reciprocating pawl carriage, a pawl on said carriage engaging said second ratchet to advance said second ratchet upon each reciprocation of the pawl carriage, a disc mounted on the shaft between the ratchets adapted to be turned by said second ratchet, a second pawl on said carriage riding on the periphery of said disc, a notch in the periphery of said disc adapted to receive said second pawl, said second pawl engaging said first ratchet when in said notch, whereby said first ratchet and shaft are advanced in unison with the second ratchet, in response to a number of advancing movements of said second ratchet and a control cam fixed to said shaft adapted to operate the washing machine clutch.

9. A timer for controlling the period of operation of a driven shaft comprising a gear case for supporting said shaft and timer, a clutch control projecting from said gear case to interrupt the drive to said driven shaft, an eccentric on said driven shaft, a pair of operatively connected rotatable timer elements, pawl means operatively connected to said eccentric and said timer elements, to advance said elements upon movement of said eccentric and driven shaft, said pawl means and rotatable timer elements constructed and arranged to rotate one of said timer elements a part of a revolution upon each rotational movement of the said eccentric and to move said other timer element in response to a pre-determined number of movements of said one timer element, means operatively connected to said clutch control and said other timer element whereby said clutch control is moved by said means in response to a pre-determined number of rotational movements of said eccentric.

10. A timer for controlling the period of operation of an oscillating driven shaft comprising a gear case for supporting said shaft and timer, a clutch control projecting from said gear case and arranged to interrupt the drive to said driven shaft, an eccentric on said driven shaft, a pair of operatively connected, rotatable ratchets, pawls operatively connected to said eccentric and said ratchets to advance said ratchets upon movement of said eccentric and driven shaft, said pawls and rotatable ratchets constructed and arranged so as to rotate one of said ratchets a part of a revolution upon each rotational movement of the said eccentric and to move said other ratchet in response to a pre-determined number of movements of said one ratchet, a cam and link operatively connected to said clutch control and said other ratchet, whereby said clutch control is moved by said cam and link in response to a pre-determined number of rotational movements of said eccentric.
